(57) **CLAIM**

The ornamental design for a paintball gun pneumatic assembly, as shown and described.

DESCRIPTION

This application is related to copending U.S. Patent Application Ser. No. 11/056,938, entitled “Pneumatic Paintball Gun,” filed February 11, 2005.

FIG. 1 is a perspective view of a pneumatic assembly for a paintball gun;

FIG. 2 is a side elevation view of a pneumatic assembly for a paintball gun;

FIG. 3 is a top plan view of a pneumatic assembly for a paintball gun;

FIG. 4 is a bottom plan view of a pneumatic assembly for a paintball gun;

FIG. 5 is a front elevation view of a pneumatic assembly for a paintball gun; and,

FIG. 6 is a back elevation view of a pneumatic assembly for a paintball gun.

The broken lines are for illustrative purposes only and form no part of the claimed design.
